ACTUATOR CONTROLLING MEANS FOR
CALCULATING MACHINES

Edwin F. Britten, Jr., Short Hills, N. J., assignor
to Monroe Calculating Machine Company,
Orange, N. J., a corporation of Delaware

Application July 13, 1945, Serial No. 604,853

4 Claims. (Cl. 192—92)

1

The invention has relation to power driven calculating machines and more particularly to means for controlling the operation of the differential actuators of such a machine and for bringing them to rest in full cycle position at the end of an operation.

The invention consists in the novel construction and combination of parts, as set forth in the appended claims.

The mechanism is a modification of that disclosed in United States Patent No. 1,566,650, issued to George C. Chase on December 22, 1925, and entitled "Operating means for calculators."

In the accompanying drawings, illustrating the invention:

Fig. 1 is a left side elevation of a machine built in accordance with the invention, with the casing removed and parts broken away.

Fig. 2 is a right side elevation of the main clutch and certain control elements therefor.

Fig. 3 is a right side elevation of the plus and minus bars.

Fig. 4 is a right side elevation of the means for closing the motor switch and disconnecting the plus and minus bars.

Fig. 5 is a detail elevation of means for centralizing the plus, minus rock shaft.

Amounts set up in known manner on the differential actuators 5 (Fig. 1) are entered in the register 13 upon operation of the differential actuators in a forward or reverse direction by the operation of an electric motor, shown diagrammatically in Figure 4.

Initiation of the operation

The operation is controlled by motor keys, shown as plus and minus bars 129, 121 (Fig. 3), having links 123, adapted through contact with an arm 124 to rock an operation control shaft 125 in a clockwise or counter-clockwise direction upon depression of a plus or minus bar respectively. Upon depression of the plus bar, for instance, the link 123 pivotally connected therewith will fulcrum upon a pin secured in the framing of the machine and will be rotated in a counter-clockwise direction as viewed in Fig. 3, and will contact with arm 124 and rock the shaft 125 in a clockwise direction.

At its left hand end shaft 125 is provided with an arm 50 (Fig. 2) having a stud engaging a slot of link 51, this arrangement providing a releasable coupling connection between operation control shaft 125 and the transmission elements controlled thereby. At its rearward end link 51 has pivotal connection with a rocker 52, pivotally

2

mounted in the framing of the machine and having toggle link connection 53 with a lever 54 fulcrumed upon the framing at 55. Depression of the plus or minus bar and rocking of shaft 125 in a clockwise or counterclockwise direction will, therefore, move the rocker 52 and break the dead center position of the toggle connection 53 in one direction or the other, this serving, as will be seen, to set the mechanism for further rotation of the rocker 52 in the selected direction and for engaging certain transmission elements (interposed in a train of drive gearing 102, 203, between the motor and the differential actuators 5) for additive or for subtractive operation respectively.

Also, the preliminary movement of rocker 52 serves to engage an auxiliary clutch and to close a switch in the motor circuit.

For this purpose an arm 56 (Fig. 1), fast with rocker 52, is rotated by said rocker out of supporting engagement with a clutch detent 51, said detent normally acting to hold a cyclically driven clutch 58 in disengaged condition. Clutch 58 is of a well-known type, wherein a pawl on the driven element of the clutch is spring urged toward a ratchet on the driving element, the clutch being disengaged upon contact of said pawl with any detent or stop supported in the framing of the machine. A clutch of this type is disclosed in U. S. Patent No. 2,243,798, issued to Herman Gang on May 27, 1941. Upon release by arm 56 detent 51 will be forced out of clutch restraining position, by the spring of the clutch pawl, and also by the spring of the switch engaging means now to be described.

Auxiliary clutch 58 is designed to engage the transmission elements effecting operation of the differential actuators, and to perform such other preliminary functions as may be necessary, and means are provided for holding this auxiliary clutch disengaged after it has effected a half cycle of rotation, the clutch being again released at the end of the actuator operation and serving during its final half cycle of operation to disengage the transmission effecting elements and to locate the differential actuators in their full cycle position. It is, therefore, necessary to keep the motor running from the time the auxiliary clutch is started until it is finally brought to rest in its full cycle position, at the conclusion of a calculation, and means are provided whereby the auxiliary clutch itself will govern the closing and breaking of the motor switch. It is, therefore, necessary to move clutch 58 out of its full cycle position in order to start the motor, and for this purpose a spring impelled arm 59 (Fig. 4) op-

erates upon a cam 60, fast upon the shaft 61 to which the driven element of clutch 58 is secured. Also fast on shaft 61 is a notched disk 62, the notched portion of which normally receives an anti-friction roller mounted upon one end of an intermediately fulcrumed lever 63. The other end of lever 63 is provided with a roller of insulating material engaging one leaf of a switch 64, interposed in the motor circuit. As detent 57 is freed from the restraint of arm 56, spring operated arm 59 will rotate cam 60 and the parts fast therewith in a counterclockwise direction as viewed in Fig. 4, this movement forcing the anti-friction roller of lever 63 onto the periphery of disk 62, whereby switch 64 will be held closed. A cam projection 65 on the driven member of the clutch serves to hold the rocker 52 in partially adjusted position (in case of a very rapid stroke on the plus or minus bar) until the clutch 58 is further rotated by the motor.

When the anti-friction roller of arm 59 drops to the low point of cam 60, a forward extension of said arm will displace an arm 74 (Fig. 4) fast upon a shaft 75. A slotted arm 76 (Fig. 2), also fast on shaft 75, has pin and slot connection with the link 51, so that as shaft 75 is rocked, upon engagement of the clutch 58, link 51 will be lifted free of the stud of arm 50 of operation control shaft 125, whereby the coupling will be broken and rocker 52 of the transmission means will be freed for additional movement and other actions will be provided for, as hereinafter set forth.

Upon the initial movement of clutch 58 a cam 66 (Fig. 2), fast on shaft 61, will be brought into contact with an anti-friction roller of lever 54, and during the remaining portion of the first half cycle of the movement of said clutch cam 66 will move rocker 52 further in the selected direction.

Fast to rocker 52 is a member 67 (best seen in Fig. 1) provided with oppositely disposed hook projections. Movement of rocker 52 following depression of the plus bar will bring one of the projections of member 67 into contact with a lug formed on a friction band 68 (Fig. 2), closing said band about the periphery of the internally-toothed gear 105 of the transmission. Closure of the band puts a spring 69 under tension to hold the internally-toothed gear 105 stationary. This transmission comprises a normally idle differential gear drive initiating and direction controlling mechanism the differential gear train of which is constructed in accordance with the disclosure of United States Patent No. 1,566,650, hereinbefore referred to. The planet pinions 103, 108 of the differential, supported on arm 104, are driven from a sun gear 102, fixed upon the motor shaft, and normally serve to drive the internally-toothed gear 105 and the spur gear 109 (Fig. 1) in opposite directions, the planet pinions rotating idly about their axis. When internally-toothed gear 105 is held against rotation, however, rotation of the planet pinions by the sun gear will cause the planet pinion assembly to be driven orbitally about the motor shaft, to rotate a gear which is in driving connection with the differential actuators 5.

Depression of the minus bar provides for the rocking of member 67 in the opposite direction, bringing the opposite hook thereof into engagement with the lug of a friction band 70 (Fig. 1) engaging the periphery of a plate 71, fast with the spur gear 109. A spring 72 is thus tensioned, to hold the spur gear against rotation, 75

whereupon the driven planet pinions will move about spur gear 109, rotating the planet assembly and the differential actuators 5 in the opposite, or subtractive, direction.

5 Clutch 58 will be released and held disengaged in midcycle position by means of a detent 73, whereby switch 64 will be held closed and rocker 52 held in extreme operated position, to maintain pressure upon the friction band of the transmission.

Termination of the operation

The differential actuators will continue to cycle until the depressed plus or minus bars are released or until the registration in the numeral wheels 13 changes from a positive to a negative character or vice versa. Thereupon, at the end of the current cycle, means will be operated for reengaging clutch 58 and for stopping and locating the differential actuators, this means being controlled by a trigger 31 (Fig. 1), and control devices similar to those disclosed in Patent No. 1,566,650.

When the plus or minus bar was depressed a plate 128 (Fig. 2) was rocked, said plate forming a part of the actuator stopping means and being connected by a coupling pawl 127 with an arm 126, fast on operation control shaft 125. Plate 128 is provided with opposed cam surfaces 30 engaging an anti-friction roller 133 mounted upon a tripping arm 134 (Fig. 1), movement of the plate in either direction thereby serving to depress the rearward end of arm 134. A spring pawl 136 is mounted on the rearward end of arm 134 and is normally held tensioned by engagement thereof with a lug of trigger 31. Upon movement of arm 134, pawl 136 is moved away from the trigger 31, and will be rotated by its spring into position underlying the lug of said 40 trigger.

A quick stroke latch 158 is moved by spring 135 into position beneath the forward extension of arm 134, holding said arm in rocked position until a cycle of the differential actuators 45 has been started. A rock arm 22, pivoted upon the framing at 23, is provided with a link 21, the other end of which has driving crank connection with a shaft 154, connected by a train of one-to-one gearing with the differential actuator shaft. During the first registering cycle rock arm 22 will be brought into contact with quick stroke latch 158, disengaging it from beneath the forward extension of arm 134 and bringing it into camming engagement with an 50 arm 169, pivoted upon arm 134 and connected therewith by a strong spring 167. Camming of arm 169 away from arm 134 will place the latter under the influence of spring 167, whereby it will be restored to normal position upon release of the key. The restoration of arm 134 55 involves the return of plate 128 to normal centralized position and, since shaft 125 is free from the link connection 51, the shaft and plate 128 will be centralized, upon release of the key, by one of a pair of spring arms 81 (Fig. 5) acting upon an arm 82 of shaft 125. In this return of arm 134 pawl 136 will contact with the lug of trigger 31, thereby raising said trigger out of contact with a pawl 25 carried upon a stopping 60 arm 24. Stopping arm 24 is pivotally mounted upon the framing at 23, and pawl 25, when released from trigger 31, will be moved by its spring into contact with the rock arm 22. As the differential actuators are rotated to their 65 full cycle position a shoulder of arm 22 will be

moved free of pawl 25, said pawl then falling behind the shoulder, to couple the arms 22, 24 together for movement as a unit. As the actuators pass beyond full cycle position arm 24 will be carried forwardly, acting through link 77 to rock the mid-cycle clutch detent 78 out of engagement with the pawl of clutch 58. Rocking of detent 78 will also bring said detent into contact with a pivoted plate 79, forcing said plate against a disk 79 whereby further rotation of the actuators in the original direction will be prevented. That is to say disk 79 will form a positive stop for arm 24 and thus for arm 22, which is in driven connection with the differential actuators. A leaf spring 80 serves to hold plate 78 normally in light contact with disk 79.

Should a change of sign occur in register 13 while the plus or minus bar is held depressed, the consequent tens transfer to the extreme left hand wheels of the register, operating through a gear 12 in driving engagement with one of the numeral wheels of the register, will operate to trip the trigger 31 and effect a stop. The coupling pawl 127 is provided in order that trigger 31, having been tripped by the action of the register 13, will not again be tripped, after the parts have come to rest, upon release of the depressed key. The coupling pawl is moved out of coupling position by contact of a pin fixed in the stopping arm 24 with an arm of said pawl.

Auxiliary clutch 58, being reengaged, will operate through its last half cycle of movement, thereby disengaging the transmission effecting elements as follows:

Cam 66 (Fig. 2) will drop away from the anti-friction roller of lever 54, and a projection 83, fixed upon said cam, will engage the upper arm of an intermediately fulcrumed lever 84, the lower arm of which is provided with an anti-friction roller engaging one of two opposed cam surfaces of the rocker 52, the roller being forced against the rocker to return it to its normal centralized position, thereby disengaging the hook of member 67 from the lug of friction band 68 or 70. There is no precise timing problem to the operation of the actuator stopping means (plate 78, etc.) and the releasing of the friction band, since if the band is first released the actuators will be carried against the stop by inertia, while if the actuators are first stopped, the gear 105 or the plate 71 will slip.

It has been said that the actuators are stopped beyond their full cycle position, and means are provided for positively returning them to such position and for holding them so located while the machine is at rest. For this purpose an eccentric 85 (Fig. 1) fast with the driven member of clutch 58 engages an anti-friction roller of a pivoted plate 155, a second anti-friction roller on said plate being driven by the eccentric against a locating cam 153 fast upon the shaft 154. Cam 153 is so designed that as clutch 58 comes to its full cycle position eccentric 85, through plate 155, will rotate the cam, the differential actuators and the parts driven therewith, in either direction back to full cycle position.

The return of the parts to full cycle position will also restore rock arm 22 to normal position, and arm 24 will be restored therewith, under the influence of a spring 28. As arm 24 comes into normal position a lug of pawl 25 will encounter the end of trigger 31 and will be lifted free of the shoulder of rock arm 22.

Rocker 52 having been restored to normal posi-

tion during the last half cycle of clutch 58, arm 56 will have relocated clutch detent 57 into the path of movement of the projecting portion of the clutch pawl, so that as the clutch is rotated to full cycle position, the pawl will be lifted out of engagement with the driving ratchet and the driven element of the clutch will be stopped.

The last half rotation of the clutch has also brought the notch of disk 62 (Fig. 4) into register with the anti-friction roller of lever 63, allowing the spring jaws of the switch 64 to separate. Spring arm 59 will also be restored and re tensioned by cam 60, and shaft 75 will be allowed to rock back to normal position, bringing the walls of the notch of link 51 again into engagement with the pin of arm 50.

I claim:

1. In a calculating machine having electric circuit means provided with a switch, a motor in said circuit, differential actuators, a normally idle transmission means between the motor and the actuators including elements engageable to effect the drive, a motor key, and actuator stopping means; a cyclic auxiliary clutch driven from the motor, means driven by the auxiliary clutch under control of the actuator stopping means to reengage the auxiliary clutch and thereby disengage the transmission elements, and devices including a notched disk operable by the auxiliary clutch to hold the switch closed when said clutch is out of its full cycle position.

2. In a calculating machine having electric circuit means provided with a switch, a motor in said circuit, differential actuators, a normally idle transmission means between the motor and the actuators including elements engageable to effect the drive, a motor key, and actuator stopping means; a cyclic auxiliary clutch driven from the motor, means operable by the motor key to release and partially rotate the auxiliary clutch, means driven by the auxiliary clutch under control of the motor key to engage the transmission elements, means for disengaging the auxiliary clutch in midcycle position thereof, means driven by the auxiliary clutch under control of the actuator stopping means to reengage the auxiliary clutch and thereby disengage the transmission elements, and devices including a notched disk operable by the auxiliary clutch to hold the switch closed when said clutch is out of its full cycle position.

3. In a calculating machine having an electric motor, differential actuators, a train of normally idle drive gearing between the motor and the actuators, a motor key, and actuator stopping means; friction elements interposed in the drive train and engageable to effect the drive, an auxiliary clutch driven from the motor, means operable through the auxiliary clutch under control of the motor key to engage and maintain engagement of the friction elements, and means operable through the auxiliary clutch under control of the stopping means to disengage the friction elements.

4. In a calculating machine having an electric motor, cyclic differential actuators, normally idle drive connections between the motor and the actuators including transmission elements engageable to effect the drive, and means for stopping the differential actuators in full cycle position; operation control devices, a releasable cou-

tion; operation control devices, a releasable cou-

pling connection between said control devices and the transmission elements, and an independently releasable coupling connection between said control devices and the stopping means.
